UNITED STATES PATENT OFFICE.

MATHÄUS Wiest, OF GRAFELFING, GERMANY, ASSIGNOR TO HANS FÜRSATTEL, OF NUREMBERG, GERMANY.

DISTRIBUTION FOR INTERNAL-COMBUSTION ENGINES.

Application filed December 26, 1924, Serial No. 758,141, and in Germany August 2, 1923.

This invention relates to single-acting and double-acting internal combustion engines in which the admission and exhaust take place in well known manner through the piston channels. The distribution is controlled by a cross pin in the piston which, in a manner known per se, effects the driving of the crank shaft and which, with this object in view, is constructed as a hollow body (cylindrical slide valve) rotating with the piston and having recesses, the gas mixture entering at the one side into this hollow body and the gases from combustion escaping at the other side from the same. The distribution may however be effected by slide valves which are arranged outside the piston at either end of the rotatable hollow cylindrical cross pin. These slide valves are hollow and have recesses on their inner sides which correspond with the outwardly directed channels of the piston. The admission of the gas mixture into the one slide valve and the exhaust of the gases of the combustion from the other slide valve takes place through the hollow space of cross pin subdivided by a partition.

Owing to the slide valves being situated outside the combustion or explosion space the security of service of the engine is increased. The slides reciprocating with the piston are rotated from the crank shaft. The movement of the crank shaft is transmitted to the slide valves preferably by a chain-gear, the sprocket wheel, of which is keyed on the crank shaft—turns around the axis of the crank shaft while being rotated at the same time by a spur-wheel gear or similar gear. A suction chamber is preferably arranged in front of the admission channel, said suction chamber being situated entirely or partly in the crank casing so that the mixture for combustion can be preliminarily heated.

An embodiment of such a distribution for double-acting internal combustion engines is shown, by way of example, on the accompanying drawing, in which:

Fig. 1 is a vertical section, and

Fig. 2 a horizontal section.

Referring to the drawings *r* are the cylinders and *b* is the piston common to the two cylinders. This piston has in well known manner on the one side the admission channels *c* and on the other side the exhaust channels *d*. Each admission and exhaust

channel terminates in a compression space *e* of the piston *b*. *a* are rotary slide valves having apertures or recesses and rotatably mounted at either side outside the piston on the cross pin *2* of the piston which in the well known manner drives the crank shaft. The rotary slide valves *a* are hollow and serve to deliver the combustible mixture to the compression spaces of the piston and to deliver the gases of combustion from the cylinders. With the cross pin *2* the connecting rods *f*, *g* of the crank shaft *h* are hingedly connected in a manner known per se. The crank shaft communicates to the slide valves *a* their rotating movement through the intermediary of a chain gear *m*, the sprocket wheel *n* of which is arranged at the side of the crank shaft *h* executes a circular movement around the axis of the crank shaft *h* being at the same time rotated from this crank shaft by means of a spur wheel gear *i*, *k*. The spur wheel *i* is mounted on a partition *u'* of the casing *u* and the spur wheel *k* is rigidly connected with the sprocket wheel *m* by means of a bolt *l*.

All the transmitting elements are arranged outside the piston and outside the cylinders. The crank casing *u* of the internal combustion engine contains also the piston and the distribution. In front of the admission channel of each slide valve *a* a suction chamber *w* is arranged which is partly situated in the casing *u*, so that the combustible mixture is preliminarily heated. The exhaust port of the cross pin *2* of the piston opens into the exhaust channel *q*. The suction chamber *w* as well as the exhaust *x* are covered and packed with regard to the casing *u* by dampers *y*. In front of the orifice of the exhaust channel *q* and in front of the orifice of a tubular socket *o* of casing *u* revolves the fly wheel *p* of the motor. This fly wheel has blades *p'* of known type which exert a sucking action upon the contents of the exhaust channel *q* and upon the contents of the casing *u* whereby a vacuum is produced in the suction channel *q*. The gases of combustion are consequently removed more rapidly from the cylinder wherefrom results an increase of efficiency of the engine. The blades of the fly wheel *p* suck further through *o* hot air from out of the casing *u* and at the same time fresh air into the same through the opening *z*. The fresh air flows along the slide valves *a* and cools the same. In each

cylinder r a tubular socket s is arranged into which the spark plug is inserted. t is the magneto which is driven from the crank shaft h by means of a corresponding gear.

5 A change speed gear can be mounted in the crank casing u and ribs v (Fig. 1) can be mounted on the outer surface of the same which are obliquely directed forward and downward. In this manner it is possible to 10 admit air permanently to the rear cylinder r as indicated in Fig. 1 by the arrow and to cool at the same time the oil in the crank casing.

The engine may be a two-stroke or a four 15 stroke motor.

I claim:—

1. An internal combustion engine, in which the admission and exhaust are effected through slots in the piston, comprising in 20 combination with a cylinder and a piston having an admission slot and an exhaust slot and a crank shaft, a hollow cross pin open at both ends in said piston, connecting rods connecting said cross pin with said 25 crank shaft, means for indirectly rotating said cross pin from said crank shaft, a partition in said hollow cross pin said cross pin having at either side of said partition admission and exhaust apertures, hollow rotary slide valves on said 30 cross pin one at either side of said partition and having apertures registering with said apertures of said cross pin and apertures registering with said admission and exhaust slots of said piston so that the gas mixture flows through one half of said hollow cross pin into the corresponding rotary slide valve 35 and thence through the admission slots into said piston from which piston the exhaust gases flow out into said other rotary slide valve and thence through the other half of said cross pin, and means for indirectly 40 rotating said cross pin from said cross shaft said means consisting of a chain gear one sprocket wheel of which is driven from the crank shaft and the other sprocket wheel of which is mounted on said cross pin so that 45 said cross pin and by it said slide valves are rotated.

the admission slots into said piston from which piston the exhaust gases flow out into said other rotary slide valve and thence 40 through the other half of said cross pin.

2. An internal combustion engine in which the admission and exhaust are effected through slots in the piston, comprising in combination with a cylinder and a piston having an admission slot and an exhaust slot and a crank shaft, a hollow cross pin open at both ends in said piston, connecting rods connecting said cross pin with said crank shaft, a partition in said hollow cross 50 pin said cross pin having at either side of said partition admission and exhaust apertures, hollow rotary slide valves on said cross pin one at either side of said partition and having apertures registering with said 55 apertures of said cross pin and apertures registering with said admission and exhaust slots of said piston so that the gas mixture flows through one half of said hollow cross pin into the corresponding rotary slide valve 60 and thence through the admission slots into said piston from which piston the exhaust gases flow out into said other rotary slide valve and thence through the other half of said cross pin, and means for indirectly 65 rotating said cross pin from said cross shaft said means consisting of a chain gear one sprocket wheel of which is driven from the crank shaft and the other sprocket wheel of which is mounted on said cross pin so that 70 said cross pin and by it said slide valves are rotated.

In testimony whereof I affix my signature.

MATHÄUS Wiest.
